[57] CLAIM

The ornamental design for a pliers, as shown and described.

DESCRIPTION

FIG. 1 is a perspective view of a pliers showing my new design;

FIG. 2 is a front elevational view thereof, with the jaw in an alternate position;

FIG. 3 is a bottom plan view of FIG. 2;

FIG. 4 is a front elevational view of FIG. 1;

FIG. 5 is a top plan of FIG. 2;

FIG. 6 is a bottom plan view of FIG. 2;

FIG. 7 is a left side elevational view of FIG. 5; and,

FIG. 8 is a right side elevational view of FIG. 5.

The characteristic feature of my design resides in the flush rivet joint portion in combination with the particular pliers shown.

FIG. 1

FIG. 2
